UNITED STATES PATENT OFFICE.

CHARLES WILLIAM SPEIRS, OF BATTERSEA, LONDON, ENGLAND, ASSIGNOR TO
MORGAN CRUCIBLE COMPANY, LIMITED, OF BATTERSEA WORKS, BATTER-
SEA, LONDON, ENGLAND.

ELECTRICALLY-HEATED FURNACE.

Application filed October 5, 1920. Serial No. 414,736.

To all whom it may concern:

Be it known that I, CHARLES WILLIAM SPEIRS, a subject of the King of Great Britain, residing at Battersea Works, Battersea, London, England, have invented new and useful Improvements in Electrically Heated Furnaces, of which the following is a specification.

This invention relates to the mounting of tubes and crucible-shape containers similar, for instance, to that shown in the specification of British Patent No. 24,626/1912, which are heated by the passage of an electric current.

15 In using tubes and crucibles of this type, it has been usual to mount them in a metal or other suitable casing, from which they are insulated by some form of refractory brick and surrounded by some form of refractory insulating material, such as soot or the like.

It is also usual to fit to terminal ends, which are preferably part of the tube or crucible, water-cooled terminals and to support the bottom terminal rigidly on (but

25 electrically insulated from) the casing.

Now, I have found in practice, more especially in the casing of crucibles and tubes of large size, requiring large water-cooled terminals, that it is difficult to fit the said 30 crucibles or tubes into the rigid terminal, so that it makes good contact and at the same time is concentric with the lining of the casing and in the correct position vertically.

35 I have also found that container resistors tend to perish, i. e., the carbon burns away, unless the air is excluded.

I have further found that the container resistors tend to become soft at temperatures 40 between 1,000° C. and 1,200° C.; also that there is a considerable expansion and contraction between atmospheric temperatures and a temperature of, say, 1,350° C.

The objects of the invention are to enable 45 me to mount the lower terminal, so that, when clamped firmly to the lower extension of the tube or crucible, the whole can be freely moved, whereby the tube or crucible can be fitted concentrically with the lining 50 and the height of the tube or crucible inside the lining can be adjusted; to make an air tight joint between the terminal and the casing; and to arrange a packing material, between the tube or crucible and the refractory

lining of the casing, which is rigid enough 55 to support the container resistor when hot and flexible enough to allow for free expansion and contraction, which packing will also exclude the air, act as a heat insulator to retain the heat, be able to withstand a 60 temperature up to 1,500° C., be chemically inert at the above temperature and have an electrical resistance that is high at high temperatures in comparison with that of the container resistor. 65

To this end the invention consists in the improvements hereinafter described and illustrated in the accompanying drawings, in which:—

Figure 1 is a sectional elevation of a crucible container embodying the improvements. 70

Figure 2 is a plan view of the upper terminal.

Figure 3 is a plan view of the lower terminal, and 75

Figure 4 is a sectional elevation of a tube container embodying the features of the invention.

Referring first to the construction illustrated in Figures 1 and 3, *a* indicates the metal casing and *b* a crucible with or without a spout, the said casing being provided at the lower part with a bracket *c* electrically insulated from it. This bracket *c* has passed through it a screw *d* the upper conical end *e* of which through the medium of a hole or recess *e*¹ in a plate or disc *f* supports the said plate on which the lower extension *g* of the crucible rests. Or the end of the screw *d* may be rounded so as to form with the recess *e*¹ a ball and socket joint. *h* indicates an air-cooled terminal which is secured upon the said lower extension *g* of the crucible on which it can be readily adjusted to the correct height and concentrically within the casing lining *i*. 85

j indicates the upper terminal which is in the construction shown, air-cooled and is furnished with arms *j*¹ sliding on guide pins *j*² fixed to the upper end of the casing *a*, 100 but electrically insulated therefrom, springs *j*³ being provided on the said pins to relieve the weight of the terminal pressing upon the top of the crucible *b*, and yet allow of expansion and contraction. 105

When both terminals *h* and *j* have been fitted with all adjustments made so that the crucible is concentric with the lining *i*, and

so that the spout (not shown) is at the correct height, a ring *k* on the lower terminal *h*, and which ring is provided with an angular edge *k*¹, is adjusted so as to press 5 against a packing ring *l* of asbestos or other suitable electrical or thermal insulating material introduced into the annular groove *l*¹ in the base of the casing *a*, thus sealing the annular space between the crucible *b* and 10 the lining *i* at the lower end.

In order, further, to provide against the admission of air around the base of the crucible, the space immediately above the lower terminal *h* up to about the level of 15 the bottom of the casing *a* (at which point there is comparatively little heat generated and no appreciable expansion) is filled with any very fine mesh powdered material, such as sand, finely ground burned refractory 20 clay or the like, which is an electrical insulator at low temperature; this filling is indicated at *m*.

After numerous experiments, I have discovered that a natural crystalline plumbago 25 of high carbon content, milled by well known methods so that flakes of a "platey" nature are produced, has (if the fine dust produced during milling is taken out) a large surface area in proportion to its mass, 30 and is a suitable material *n* for surrounding the crucible or tube at the high temperature zone. This material, if poured and not too tightly pressed into the annular space surrounding the crucible at the high temperature 35 zone, has all the desired requirements, viz, it is rigid enough to support the crucible walls when hot, it will allow free contraction and expansion, being very springy, it tends to exclude all air, it is a 40 very good heat insulator, probably due to voids between the particles, it is quite unaffected and inert up to temperatures of about 1,500° C., and also, owing to high contact resistance between flake and flake, 45 it has a high electrical resistance compared with the crucible resistor.

As the lower terminal *h* is fixed, all the movement of the crucible takes place at the top terminal, and consequently free movement 50 must be provided for at this point, and I find it best to fill the annular space up to the level of the top of the case with flake plumbago, as above described, and to retain this in position, when tilting the case, 55 by means of a light asbestos ring *o* which is quite able to withstand the low temperature near the top water-cooled terminal. This ring is advantageously secured in position by a metal ring *o*¹.

60 Figure 4 shows the invention applied to an electrically heated tube *b*. In this case, the plate or disc *f* hereinbefore described, is dispensed with and, in lieu thereof a ring *p* is provided, which supports, but is electrically insulated from, the lower terminal 65

h which, in this case, is shown water-cooled. The tube *b* is adjustably carried by means of studs *q* depending from the bottom of the casing *a*, which pass through lugs *p*¹ on the ring *p*. *r* indicates a ring which is 70 screwed into the base of the casing *a* above the lower water-cooled terminal *h*, the said ring, when the terminal is fixed in position, being screwed downwards until its annular lower edge makes contact with an insulating 75 ring *s* of asbestos or the like, provided upon the top of the said terminal, thereby forming a joint which closes the lower end of the annular space between the tube *b* and the lining *i*. The top terminal *j*, which, in this 80 case, is also shown to be of the water-cooled type, is supported in a manner similar to that described with reference to the furnace illustrated in Figures 1 to 3, and the annular space between the tube *b* and the inner lining 85 is likewise filled with a special flake graphite *n*, as hereinbefore described.

Electrically heated tubes mounted as herein described and illustrated in Figure 4, may also be used in the horizontal position 90 or as a muffle furnace. In this latter arrangement the tube is mounted horizontally and is provided with a refractory slab extending the complete length of the tube, the said slab acting as a floor or carrier for 95 the charge, and forming thereby a D-shaped furnace of the well known forms.

Claims:

1. An electrically heated melting furnace, 100 provided with a plate for supporting a crucible, said plate being carried through the medium of a centering device by means attached to the base of the furnace casing.

2. An electrically heated melting furnace 105 as claimed in claim 1, in which the centering device comprises a bolt and nut construction, said bolt being beveled at the upper end to engage an orifice in the supporting plate.

3. A furnace as claimed in claim 1, in 110 which the means which carry the supporting plate consist of a bracket.

4. In an electrically heated melting furnace, the combination with a crucible, of an upper terminal having one or more arms which slide upon guide pins, said guide 115 pins being provided with springs for taking the weight of the terminal from the crucible.

5. In an electrically heated melting furnace, the combination with a tubular melting container, of a lower terminal, a supporting ring for said terminal, adjustably carried by the base of the furnace casing and insulated from said terminal. 120

6. An electrically heated melting furnace 125 as claimed in claim 5, in which the lower end of the annular space between the tube and the casing lining is provided with a joint.

7. An electrically heated melting furnace 130

as claimed in claim 5, in which the lower terminal is provided with a metal ring, adapted to contact with the packing ring of electrical and thermal insulating material carried by the case of the casing.

8. An electrically heated melting furnace as claimed in claim 5, in which the lower end of the annular space between the tube and the casing lining is provided with a joint, a ring adjustably fitted to the base of the casing and adapted to contact with an

insulating ring provided upon the upper face of the lower terminal.

9. An electrically heated melting furnace provided with a resistor and a refractory wall and a packing between said resistor and wall consisting of a natural crystalline plumbago.

10. An electrically heated melting furnace as claimed in claim 9, in which the plumbago package is of a "platey" nature.

CHARLES WILLIAM SPEIRS.
